UNITED STATES PATENT OFFICE.

SAMUEL G. CABELL, OF QUINCY, ILLINOIS, ASSIGNOR TO HIMSELF AND GEORGE P. ESTE, OF WASHINGTON, DISTRICT OF COLUMBIA.

IMPROVEMENT IN FOG-ALARMS.

Specification forming part of Letters Patent No. 117,861, dated August 8, 1871.

To all whom it may concern:

Be it known that I, SAMUEL G. CABELL, of Quincy, in the county of Adams and in the State of Illinois, have invented certain new and useful Improvements in Fog-Signals; and do hereby declare that the following is a full, clear, and exact description thereof, reference being had to the accompanying drawing and to the letters of reference marked thereon making a part of this specification.

The nature of my invention consists in a fog-signal or alarm, in which one or two cylinders, a horn, and a piston are used, as will be hereinafter more fully set forth.

In order to enable others skilled in the art to which my invention appertains to make and use the same, I will now proceed to describe its construction and operation, referring to the annexed drawing, in which—

Figure 1^a is a longitudinal vertical section, showing one cylinder working outside of another and a piston working in the inside cylinder. Fig. 1^b is an end view of Fig. 1^a. Fig. 2^a is a longitudinal vertical section, showing a piston working in a single cylinder. Fig. 2^b is an end view of the cylinder in Fig. 2^a. Fig. 3 is a longitudinal vertical section, showing a modification of Fig. 1^a. Fig. 4 is a side view, showing still another modification.

A represents a cylinder, closed at one end by means of a head and stuffing-box, *a*, through which the piston-rod *B* passes. At a suitable distance from the other end, within the cylinder *A*, is a partition, *C*, in which the reed *D* of the horn is screwed. This end of the cylinder should extend so far beyond the partition *C* that when the horn is inserted the end of the cylinder and sides of the horn will form a close joint. On the inner side of the partition *C* is attached the apex of a cone, *E*, surrounding the reed *D*, and the sides of said cone are attached to the sides of the cylinder *A* below the end of the reed. This cone collects the air and drives it toward the reed at the same time as it acts as a stop for the piston, preventing the same from coming in contact with and injuring the reed. Surrounding and moving up and down on the cylinder *A* is another cylinder, *G*, closed at its outer end, and provided at said end with an inwardly-opening air-valve, *b*. The inner end of the outer cylinder *G* is, by a stuffing-box, *d*, kept tight with the

outside of the inner cylinder *A*. The outer end of the cylinder *G* is provided with a handle, *H*, and the piston-rod *B* is attached to this end of said cylinder in the center. The piston-rod *B*, as above mentioned, passes through the stuffing-box *a*, and is, within the cylinder *A*, provided with a piston, *L*. The rod *B* is hollow, and provided with one or more elongated slots, *e*, near its outer end, so that the air from the cylinder *G* can pass through the piston-rod into the cylinder *A*.

When the cylinder *G* is drawn out the piston *L* is drawn at the same time to the outer end of the inner cylinder *A*. The piston draws air into the inner cylinder through the horn, while the valve *b* admits air into the outer cylinder *G*. When this cylinder is now pressed inward the air in the inner cylinder, together with the air from the outer cylinder passing into the former through the piston-rod, becomes compressed and sounds the horn.

This principle may be applied in a number of ways, some of which I have shown in the drawing; all, however, involving my main feature, namely, one or more cylinders, a horn, and a piston.

In Fig. 2 I have shown a single cylinder, *A*¹, with reed *D* and cone *E*. The outer or lower end of this cylinder is open, and a piston, *L*, works in the same. The piston-rod *B*¹ is solid, and attached to a handle, *H*¹. From this handle rods *f* pass down through tubes *h h* attached longitudinally on the outside of the cylinder *A*¹. These rods act as guides for the piston, and the tubes strengthen the cylinder.

In Fig. 3 I have shown a cylinder, *A*², with reed *D* and cone *E*. Inside of this cylinder works another cylinder, *G*², closed at its inner end, with an air-passage, *b*², through the same. Within the cylinder *G*² moves the piston *L* and piston-rod *B*² attached to a handle, *H*². In this case the piston and cylinder *G*² work independently of each other, and this cylinder is filled with air from the cylinder *A*² through the passage *b*².

In Fig. 4 I have shown still another modification. *A*³ is the cylinder, with piston *L* and rod *B*³ passing through a cap or stuffing-box on the end. At the other end of the cylinder is a two-way cock, *I*, with a rubber bulb or other air-chamber, *J*, on the end. Above this is a bell or inverted cone-shaped piece, *K*, in which the reed

of the horn is screwed. The cock I is turned so that, by drawing the piston, the bulb J will be filled with air; then shut off the cock and push in the piston; and, whenever necessary to sound the alarm, only turn the cock, when the compressed air in the bulb will sound the alarm.

Having thus fully described my invention, what I claim as new, and desire to secure by Letters Patent, is—

1. The combination herein shown, in a fog-alarm, of one or more air-cylinders, a reed, horn, and a piston-head working in the cylinder or cylinders, substantially as and for the purposes set forth.

2. The combination of the two cylinders A and G, piston-rod B, and piston L, and an air-valve, b, arranged in the head of the cylinder, substantially as and for the purposes set forth.

3. In combination with the air-cylinder in a fog-alarm provided with a reed operated upon by a piston, the cone E, under the arrangement shown, for protecting the mouth-piece and bracing the cylinder, substantially as herein set forth.

4. In combination with the air-cylinder A¹ provided with its exterior tubes h, cone E or its equivalent, and reed D, the piston-rod B¹, pis-

ton L, and guide-rods f, all substantially as and for the purposes herein set forth.

5. The combination of the outer cylinder A², provided with reed D and cone E or its equivalent, the interior working cylinder G² having a piston-head and air-passage, b², on its inner end, and the piston-rod B² with piston L, all substantially as and for the purposes herein set forth.

6. In combination with the cylinders A and G, constructed substantially as described, the hollow piston-rod B provided with openings e, and piston L, substantially as and for the purposes herein set forth.

7. The combination, in a fog-signal, of an air-cylinder, A³, piston-rod B³, piston L, flexible air-bulb J, regulating-cock I, and a chamber inclosing a reed, D, connected with a horn, all substantially as and for the purposes herein set forth.

In testimony that I claim the foregoing I have hereunto set my hand this 21st day of July, 1871.

S. G. CABELL.
